UNITED STATES PATENT OFFICE.

DANIEL E. KEMPSTER, OF BOSTON, MASSACHUSETTS.

METAL-ROLLING MACHINE.

SPECIFICATION forming part of Letters Patent No. 380,759, dated April 10, 1888.

Application filed February 29, 1888. Serial No. 265,740. (No model.)

To all whom it may concern:

Be it known that I, DANIEL E. KEMPSTER, a citizen of the United States, residing at Boston, in the county of Suffolk and State of Massachusetts, have invented certain new and useful Improvements in the Manufacture of Articles in Metal; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in the manufacture of articles in metal having circular cross-sectional area; and the object and purpose of my improvements are to provide mechanism whereby said articles may be 20 more speedily and more economically produced than heretofore, and also to impart, by a peculiar action of the said mechanism, superior qualities to the article manufactured thereby.

25 My invention consists in the construction and combination of the various devices herein described, which thereby constitute an improved and thoroughly equipped and organized metal-rolling mill or system whereby articles may be rolled and formed into shape direct from a coil of wire rod, or from metal bars or blanks fed therein, and all the devices and appliances constituting said system as a whole acting and operating continuously and automatically to expeditiously accomplish the desired end, as will now be fully described, and 35 specially pointed out in the claims.

In the drawings, and in which similar letters of reference indicate corresponding parts, 40 Figure 1 is a central vertical section of my improved continuous metal-rolling mill; Fig. 2, a cross-section on the line A B in Fig. 1; Fig. 3, a cross-section on the line C D in Fig. 1; Fig. 4, a side elevation of one of my improved die-rolls; Fig. 5, an end view of the same; and Fig. 6 is an elevation of one of my improved spheres or balls as rolled and formed in my improved rolling-mill.

45 My invention is susceptible of being constructed and arranged in a variety of ways, and may be modified to suit the class of work

to be rolled or formed thereby, always retaining, however, my combinations of devices, as herein set forth, as being the essential elements for constituting an organized automatic 55 system or continuous metal-rolling mill.

For a certain kind of work I find it convenient to construct and arrange the mill in the form shown in the accompanying drawings, in which $a a' a''$ represent a suitable frame 60 for supporting the various devices, and having a base-plate provided with holes for securing it to the floor in the usual manner with power machinery. The frame is provided with bearings 1 2 3 4 for supporting the 65 journals of the die-rolls $b b$. Said bearings are constructed with caps in the ordinary manner, so as to be able to readily remove said dies therefrom. The bearings 1 and 2 are formed in extending and integral portions of 70 the frame a ; but the bearings 3 and 4 are formed in the portion a' , made separate therefrom and supported by and between suitable ears on the main frame, two of said ears being slotted to receive tightening screws 5 and 6, 75 which screw into oppositely arranged ears, whereby the part a' may be clamped solid between the said frame-ears and thus be held firm and rigid with said frame.

The piece d is backed up by the wedge-piece a'' , which is suitably tongued by T-headed screws, as shown, to slide in correspondingly-formed grooves in said part a' and the tapering portion of the main frame a , thereby connecting said parts together, so that when 85 the wedge a'' is raised or lowered by the screw 7, which passes through the top plate, a^3 , and screws into said wedge, the piece a' is caused to move bodily out or in between its supporting-frame ears, and may be held rigid at any 90 point in the limit of its movement by tightening up the clamp-screws 5 and 6, before referred to.

The die-rolls $b b$ are connected, so as to revolve together at the same speed and in the 95 same direction, by suitable gearing, two of which, $c c$, are fast on the die-roll shafts $c' c''$, and the intermediate gear, d , runs loosely on the T-headed stud e , which is adapted to slide laterally in the top of the stand f , fast on the 100 base a , said stud e being held in such position therein by the connecting-links $e' e'$ as to in-

sure the proper meshing and working of said gearing, regardless of the positions of the die-rolls or the distance between them.

The die-roll journaled in the solid side of 5 the frame is provided with the shaft c' , and it extends downward and rests in a step or bearing, c^3 , on the base a . Said shaft has fast thereon the bevel-gear g , which meshes with a corresponding gear, h , on the horizontal shaft 10 i . Said shaft is supported in boxes $i' i''$, and is provided on its outer end with a fast and loose pulley, as is usually employed on machinery.

The shaft i has securely fastened thereon the 15 double-throw cam j . A feed-lever, k , pivoted on the side of the frame, has a stud and roll, which runs in the groove of said cam and is vibrated thereby. The upper end of said lever has a pivoted pawl, k' , and spring k'' . Said 20 spring has a projection on its end, which engages the pin k^3 on the pawl, and by throwing said pawl up or down, so that said projection engages said pin on opposite sides, the said pawl may be held out of or into engagement 25 with its feed-ratchet.

As shown plainly in Fig. 3, the feeding mechanism consists in two corrugated feed-rolls, $m m$, keyed fast on the ends of two shafts, $m' m''$. Said shafts are supported at their ends 30 nearest said feed-rolls by the half-boxes $8 8$, adjustably held between the ears $9 9$ on the die-roll bearing-caps. Said boxes may be adjusted, so as move the shafts and cause said feed-rolls to grip the metal rod 10 more closely, by setting up the screws $11 11$, which are provided 35 with suitable check-nuts thereon for holding said screws in position when once properly adjusted and set. When necessary to separate said feed-rolls, the said screws are slackened, 40 so as to allow said boxes to be separated by the pressure of the spring l , which is fast on the feed-stand n and bears against the inner sides of the feed-roll shafts.

The stand n is attached to the bottom of the 45 top plate, a^3 , and supports the outer end of the shaft m' in the box o , and also the outer end of shaft m'' in the half-box o' . Said shafts have fast thereon, just outside of said boxes, the intermeshing feed-gears $p p$. Said 50 gears have solid collars on their sides, as shown, which are adapted to run together with a certain amount of frictional contact produced by pressure exerted by the screws $q q$ in the feed-stand n . The shaft m' has also 55 fast thereon, outside of its feed-gear p , a notched disk, r , and feed-ratchet s . The disk r is provided with the detent r' , pivoted on an arm on the stand n , and is adapted to be pressed into one of the notches in the disk r by the spring 60 r'' , also on said arm, and thus, with the aid of the friction created by the feed-gear collars before referred to, the feed-rolls $m m$ are held steady while the pawl k' is being drawn back by its lever k , through the medium of the 65 grooved cam j , to engage another tooth of its ratchet s , preparatory to feeding in another piece of the metal rod, sufficient for a blank,

which is severed therefrom by the cutters $b' b'$ $b' b$, fastened on the ends of the die-rolls $b b$. The ratchet s has just a sufficient number of 70 teeth thereon to insure its feeding into the cutters and dies the proper amount of metal to be rolled down and condensed into shape, and in passing through said dies becomes a perfectly-formed article.

A stand, a^4 , is attached to the top of the top plate, a^3 , and the furnace t is attached thereto. Said furnace is lined with asbestos or fire-brick, usually employed for this purpose, and is provided with a door, t' , through which to 75 inspect the interior. Said furnace is contracted or shaped so as to concentrate the heat closely around the metal rod near the feed-rolls, and is also constructed with a top plate or cover, t'' , held to the outer shell or casing 80 by suitable screws, so as to be readily removed for the purpose of relining said furnace, or otherwise.

The furnace is provided with a powerful blow-pipe, composed of the gas-pipe t^3 , which 90 enters and is surrounded by the air-blast pipe t^4 , said air-blast being controlled by the valve t^5 , and the gas being controlled by the valve t^6 . Said blow-pipe enters the furnace through 95 its cover or top plate, and delivers its flame or blast nearly parallel with the metal rod being heated, and drives the heat forward toward the feed-rolls where desired to be the hottest.

As shown in Fig. 1, the top plate, a^3 , is formed with a hole through its center to permit the nose-piece of the furnace to enter close up to the feed-rolls; and also it will be observed that the base-plate or bed of the mill is provided with a hole through the same directly under the working-center between the 105 die-rolls. This is for the purpose of allowing the articles being rolled or formed to drop direct from the dies into a receptacle or cooler, 12, under the mill, containing a liquid preparation for throwing off the scale formed thereon 110 by the usual oxidation; and, if desired, said liquid may also harden and temper said articles by adding suitable ingredients to said cooling preparation.

Extending upward from the top of the stand 115 a^4 are two forked arms, a^5 , on which is suspended the reel u , having the coil of metal rod 10 thereon. Said reel is free to revolve on bearings in said forked arms, and as the said rod passes off from said reel it is guided by the 120 guide-piece a^6 on the stand a^4 , and, passing through the furnace t , enters between the corrugated feed-rolls $m m$. The outer end of the feed-roll shaft m' is squared to receive a crank 125 for the purpose of revolving said feed-rolls by hand, and thus embrace and feed in the end of the metal rod when first starting the mill.

By referring to Figs. 1 and 4 it will be seen that the die-rolls $b b$ are straight cylinders arranged side by side, and are each provided 130 with two tapering working-grooves, $b'' b''$, arranged therein obliquely to the line or plane of their movement, or running spirally around said die-rolls in the same direction.

Said grooves are arranged on said rolls diametrically opposite each other in a similar manner to a double-threaded screw, and said rolls are geared together in a manner to cause 5 said grooves on opposite die-rolls to register with each other as said rolls are revolved in the same direction. It should also be observed that as said rolls are revolved in the same direction their adjacent and opposed faces are 10 moving in opposite directions, and therefore, owing to the spiral form of the working-grooves, the registering-point of said grooves is constantly changing from one end of the die-rolls to the other, and a metal blank severed 15 from the rod by the registering-cutters on opposite die-rolls and entering the flaring ends of the registering die-grooves would be bodily confined therein, and as it was being rolled and condensed into shape would be conveyed 20 along within said grooves between the two die-rolls in a straight line parallel with the axes thereof until it was forced out of the ends of said grooves at the opposite ends of said die-rolls.

25 The working-grooves *b*" of the die-rolls are properly tapered and scored or milled throughout a portion of their length, so as to allow the metal blank to enter freely between them, and then revolve, roll, and condense said blank 30 into the form of a sphere or ball, the die-roll grooves in this case being formed in cross-sectional area of a shape to produce said article, although any other form of article may be made by so shaping the die-grooves. It should 35 be noticed that by my having the double cutters and grooves on the die-rolls, and the feed-cam also double-throw, I am able to roll and form two spheres or other articles at every complete revolution of the said die-rolls, and 40 I may still increase that number, if so desired, by adding more cutters and grooves to the dies and corresponding movements to the feeding mechanism. Also by my giving a quick pitch to the spiral die-grooves I obtain a spirally-rolling movement of the spheres being 45 formed thereby, which more evenly condenses the metal and produces a sphere in which the grain or fibers of the same are running through it spirally in every direction, as shown in dotted lines in Fig. 6, thus producing a superior 50 and improved article of manufacture, as must be apparent, and another and separate application will be filed by me in the Patent-Office therefor hereafter.

55 In rolling and forming spheres as heretofore practiced—that is to say, with dies having their working-grooves formed in line with the line or plane of their movement—said spheres are rotated about their own centers, said centers 60 being joined to the metal rod, each side of the blank being rolled and formed, and is only separated therefrom at the very last part of the operation, and consequently the portion of metal which was on the end of the rod and 65 outside of said blank is always wasted; and, furthermore, it is exceedingly difficult and not practicable to adjust the opposing faces of the

dies near enough together to form a perfect sphere, as the die-surfaces are moving in opposite directions, and therefore cannot bear 70 against each other with great pressure, as in ordinary rolling where the contacting surfaces of the dies are moving together in the same direction, and cannot prevent leaving a small projection or point upon opposite sides of the 75 sphere, where the die-rolls cannot be forced together close enough to prevent it, without creating too great a friction; and spheres rolled and formed in this manner have the metal very unevenly condensed, as the greatest compression comes on the sides of the blank next to the metal rod, as the dies must condense and draw in the metal at those two points in order to separate said blank from said rod. This necessarily strains the outer portion of the 80 metal sphere, so that in hardening or tempering said spheres the unequal expansion and contraction of the metal under different degrees of tension throughout its parts develops minute fractures or "fire-cracks" running 85 concentrically around what were the original centers or axes of rotation of said spheres while being rolled and formed. Such spheres, when used in the bearings of bicycles and other wheeled vehicles, break apart in the 90 form of laminations, and often, like the shell of a nut, leaving a kernel or small sphere among the broken pieces.

My improved mill and method of manufacture effectually overcome all of the above objections and defects, as, first, I waste no metal, only enough being severed from the rod each time to form a complete article; second, I am able to run the mill with the die rolls separated, so as to avoid any friction between their 100 adjacent and oppositely-moving faces and yet produce perfectly-formed spheres thereby by reason of the spirally-rolling movement given said spheres in their passage through said dies; third, a stronger, more homogeneous, 105 and more perfect sphere is produced than heretofore, and, fourth, I am able to greatly cheapen the cost of manufacture, as my mill is continuous and automatic in its operations and is capable of being run up to any speed 110 within the limits of the capacity to heat the metal rod, and for certain kinds of work which can be formed of cold metal the speed may be 115 further increased.

The operation of my invention is as follows: 120 A coil of metal rod is placed upon the reel and suspended in the forked bearings overhead. The furnace is lighted up and the gas and air properly adjusted, so as to give the greatest amount of heat. After the furnace has become 125 thoroughly hot, the end of the metal rod is passed down through it and in its passage becomes white hot. As the end of said rod comes against the feed-rolls, they are revolved by hand with a suitable crank applied on one of 130 the feed-roll shafts until the end of the rod enters and is fed up against the bottom of the registering die-grooves, the mill having been revolved by hand previously to bring said

grooves in proper position. The crank is then removed from the feeding mechanism and the driving-belt shipped onto the fast pulley, revolving it in the direction of the arrow shown thereon, and through the bevel and other gearing the die-rolls are caused to revolve together in the direction of the arrow shown in Figs. 4 and 5. As the registering cutters come together, a blank is severed from the rod just as the die-grooves grasp it and start or commence to roll and revolve it between their oppositely moving and contracting forming-surfaces. The feeding mechanism in its proper time keeps driving the end of the metal rod into the successively-registering die-grooves, and the adjacent cutters as often sever a blank therefrom, two to every complete revolution of the die-rolls, and at the proper working speed a continuous stream or series of metal blanks are entering one end of the said die-rolls and are passing out the opposite end completely rolled and formed, and are immediately cooled by a suitable air-blast or the cooling liquid, as before stated.

I have shown herein the mill arranged in a vertical position; but I may arrange it horizontally, and I so prefer it for some kinds of work, as the scale from the heated rod is not so liable to fall into the dies and be rolled into the article being formed; also, I do not desire to limit my invention to the exact construction herein specified, as it may all be varied without departing from the essential spirit thereof, and, therefore, I may vary the number of cutters and die-grooves, or vary the form of dies employed, or vary the shape and taper of their working or forming surfaces to suit the particular shape in cross-section of the article to be produced by rolling; also, the cutters may be a single pair or ordinary wire-cutters attached to a stationary part of the mill between the feed-rolls and dies, and be operated by suitable mechanism, if so preferred, and, also, the blanks may first be all cut into proper length and be heated in a suitable furnace and automatically fed therefrom into the dies by suitable automatic feeding mechanism; and for the manufacture of a heavy class of spheres and other articles I prefer to thus modify the arrangement of the mill, such modification requiring no illustrating in the drawings herein submitted, as any skilled mechanic would readily understand how to accomplish it or change the relative positions of the various devices composing the mill to best accommodate the class of work to be rolled therein; and I would state in this connection that for certain kinds of heavy work I sometimes use in my improved mill dies as usually formed—that is, having their working faces or grooves formed in a line with the line or plane of their movement. This necessarily makes the operation of rolling considerably slower, as the article when formed must drop, by its own gravity, out of the dies before another blank can be fed into them, whereas with my improved dies said

blanks are thereby automatically conveyed out of the way of each other, which therefore admits of running the mill at any desired speed. However, as before stated, for certain kinds of work I may use dies constructed in the old and well-known manner, and in connection with my improved mill their utility and capacity are greatly increased.

I have not herein minutely described the action of cross-rolling metal into various forms circular in cross-section by oppositely-moving die-surfaces, as it is an old and well-known method of rolling metal; neither have I described the various forms of dies to which my improved die-grooves may be applied, nor the various articles which may be rolled and formed thereby, as these matters have been fully gone into in another application filed by me in the Patent Office.

As shown in the drawings, the die-rolls may be adjusted to vary the size of the article being formed, and by varying the number of teeth in the feed-ratchet more or less metal stock may be put into the blank. By arranging the die-rolls in a vertical position, I am able to run the metal through the dies without any intermediate guides between them, said guides being objectionable on account of their creasing or marking the hot plastic metal in its passage through said dies. The vertical position of the dies also admits of dropping the finished article down plumb into the cooling-liquid without the use of any conductor or spout to guide it thereto, and therefore the liability is avoided of the hot finished article striking any obstruction which would be liable to mar or injure the perfect configuration or surface of the same before its entering and becoming cooled by the liquid provided therefor.

For heavy kinds of work it is necessary to make use of metal bars or rods instead of using from a coil of wire; but in either case it should be understood that the main bar or rod does not revolve, but is simply fed along longitudinally into the mill, and metal blanks are successively severed therefrom and then revolved and rolled by the dies, whereby said blanks are condensed and formed into the shape of the finished article in their passage through or between said dies.

It will be observed that the cutters *b'* are removably attached on the die-rolls by suitable screws to admit of repairing or adjusting them after prolonged and continued use.

Having now described the nature of my invention, I desire to secure by Letters Patent and claim—

1. In an organized continuous metal-rolling mill, the combination of two dies having their adjacent working-faces adapted to move in opposite directions with cutters for automatically severing the metal blank from the rod prior to rolling and forming said blank, for the purpose set forth.

2. In an organized continuous metal-rolling

mill, the combination of two dies having their adjacent working-faces adapted to move in opposite directions and cutters for automatically severing the metal blank from the rod 5 with feed-rolls for automatically feeding said rod into the mill, for the purpose set forth.

3. In an organized continuous metal-rolling mill, the combination of two dies having their adjacent working-faces adapted to move in opposite directions, cutters for automatically severing the metal blank from the rod, and feed-rolls for automatically feeding said rod into said dies and cutters with a furnace for heating said rod, for the purpose set forth.

15 4. In an organized continuous metal-rolling mill, the combination of two dies having their adjacent working-faces adapted to move in opposite directions, cutters for automatically severing the metal blank from the rod, feed-rolls for automatically feeding said rod into said dies and cutters, and a furnace for heating said rod with a reel or support for holding said rod, for the purpose set forth.

25 5. In an organized continuous metal-rolling mill, in combination, two dies having their adjacent working-faces adapted to move in opposite directions, automatic cutters, automatic feeding mechanism, and a reel or support for holding the metal rod or bar, substantially as and for the purpose set forth.

35 6. Two die-rolls provided with working-grooves formed obliquely to the line or plane of their movement and two parallel shafts carrying the said die-rolls, combined with each other and with gearing to rotate the said die-rolls in the same direction, to operate substantially as described.

7. Two die-rolls provided with working-grooves formed obliquely to the line or plane 40 of their movement and two shafts carrying the said die-rolls, combined with each other and with gearing to rotate said die-rolls in the same direction, and with mechanism for adjusting the distance between said die-rolls, substantially as and for the purpose set forth.

45 8. Two die-rolls provided with working-grooves formed obliquely to the line or plane of their movement and two shafts carrying the said die-rolls, combined with each other and with gearing to rotate said die-rolls in the same direction, and with feed-rolls for supporting and feeding the metal blank into said die-rolls, for the purpose described.

9. Two rotating die-rolls mounted in bearings 55 and provided with working-grooves formed obliquely to the line or plane of their movement and scored or milled to aid in rotating the blank being acted upon within said grooves, combined with each other and with gearing to 60 drive the said die-rolls in the same direction at the same surface speed, the registering-point of the said working-grooves between the said die-rolls constantly changing from one end of said die-rolls to the other, and thereby in rolling, condensing, and forming the metal blank

65 said blank is bodily conveyed along within said die-grooves in a straight line parallel with

a central line between said die-rolls, for the purpose described and set forth.

10. In combination, the supporting-frame 70 and the rolls supported thereby and having oblique working-grooves tapering from their finishing to their starting ends, substantially as described.

11. A die-roll having a working-groove 75 formed obliquely to the line or plane of its movement and having a cutter on its starting or blank-entering end, substantially as and for the purpose described.

12. The die-rolls *b*, having cutters *b' b'* and 80 grooves *b'' b''*, substantially as shown and described.

13. In combination, the frame *a a' a''*, the wedge *a''*, and adjusting-screw 7, substantially as described. 85

14. The shaft *i*, cam *j*, lever *k*, and pawl *k'*, in combination with the feed-ratchet *s*, adjustable shafts *m' m''*, feed-rolls *m m*, and connecting mechanism, substantially as described, for supporting and operating said devices, for the 90 purpose set forth.

15. In combination, the feed-shafts *m' m''*, the feed-rolls *m m* and friction-gears *p p* thereon, the notched disk *r*, spring-detent *r'*, stand *n*, and connecting mechanism, substantially as 95 described, to operate in the manner set forth.

16. The frame composed of the stationary parts *a a' a''* and movable part *a'*, in combination with mechanism for adjusting the position of said movable part and means, substantially 100 as described, for rigidly securing it to the stationary part, as set forth.

17. In combination, the frame or bed, the shaft *i*, suitably supported thereon, the bevel-gears *h g*, the shafts *c c''*, the gears *c c* thereon, 105 connected with links *e' e'*, the intermediate gear, *d*, suitably supported on the frame or bed *a*, and the die-rolls *b b*, supported in the bearings 1 2 3 4 so as to revolve therein and be adjustable to or from each other, to operate substantially as described. 110

18. The die-rolls arranged in a vertical position, substantially as described, combined with feeding mechanism arranged so as to feed the blank metal vertically into said die-rolls, 115 for the purpose substantially as set forth.

19. The frame and its top plate, combined with the stand *a'* and rod-supporting reel *u*, substantially as described.

20. The stand *a'*, having forked arms or reel-bearings *a''* and rod-guide *a''*, combined with the furnace *t* and means, substantially as described, for heating said furnace, for the purpose set forth. 120

21. The furnace constructed with one end 125 contracted so as to concentrate the heat, as described, and the other end provided with a removable cover, for the purpose set forth, in combination with the blow-pipe or means for heating said furnace, substantially as and for 130 the purpose specified.

22. The frame *a a'* and wedge *a''*, constructed and combined as described, whereby a longitudinal movement of said wedge in either di-

rection gives a corresponding lateral movement to the frame a' , substantially as and for the purpose described.

23. The frame a a' and screws 5 6, substantially as and for the purpose set forth.

24. The shaft i , suitable bearings, i i'' , therefore, the feed-cam j on said shaft and provided with a double-throw groove, as described, the lever k , pivoted on the side of the mill and provided with a stud and roll for running in said cam-groove, as set forth, and the pawl k' and its spring k'' , all combined to operate

substantially as described, for the purpose set forth.

25. The combination of an automatic continuous metal-rolling mill with means, substantially as described, for scaling and cooling the hot finished articles, as set forth.

In testimony whereof I affix my signature in presence of two witnesses.

DANIEL E. KEMPSTER.
